Specification of Letters Patent.

Patented Dec. 2, 1913.

Application filed December 30, 1911. Serial No. 668,794.

To all whom it may concern:

Be it known that I, AMOS CALLESON, a citizen of the United States, residing at Brooklyn, in the county of Kings and State 5 of New York, have invented certain new and useful Improvements in Machines for Operating on Sheet Material, of which the following is a specification.

This invention relates to machines for 10 forming articles of sheet metal, and particularly to that class of such machines which are adapted to operate upon sheet material that is two or more times wider than the diameter of the cut whereby each article is 15 formed. Usually in these machines a gang of two or more dies is employed, such dies at each operation forming a row or series of cuts that is substantially coextensive with the width of the sheet. In the present 20 instance, however, but a single die is employed, and in order to make clear how the die is made to operate upon all parts of the sheet it may be well to preface the following detailed description of the invention 25 with a brief outline of the steps performed.

The die is made to produce cuts one after another in rows or series, the rows being parallel, and as fast as each row is formed the apertured part or scrap portion of the 30 sheet is removed, thereby allowing the sheet to be shifted transversely so as to stand within the effective range of the die for the cutting of the next adjacent row of cuts. Preferably, instead of beginning the cutting 35 of the several rows at the same edge of the sheet, the odd rows are started from one edge and the even rows from the opposite edge of the sheet so that during the feeding of the sheet in each direction a row of 40 cuts will be produced.

Two embodiments of the invention are disclosed herein: In one the feeding of the sheets to form each row of cuts is performed 45 by hand under automatic control, the transverse shifting of the sheet after the scrap appertaining to a finished row of cuts is removed being accomplished by the action of gravity on the sheet; in the other the operation is substantially completely automatic, 50 the attendant having merely to supply the machine with sheets one after another and start it when it automatically stops upon completing its work upon any one sheet.

In the accompanying drawings, Figure 1 55 is a side elevation of the machine; Fig. 2

is a front elevation; Fig. 3 is a plan view illustrating the table on which a sheet is supported while being operated upon and parts of a die mechanism, severing means and means for controlling the planiform movements of said sheet; Fig. 4 is an end elevation of the sheet support; Fig. 5 is a transverse sectional view taken substantially centrally of the die mechanism and showing said die mechanism and parts of 60 the means for controlling the planiform movements of a sheet; Fig. 6 is a plan view of one of the sheet severing means and parts of its controlling mechanism; Fig. 7 is a front elevation of the two severing means 65 and parts of their controlling mechanism; Fig. 8 is a side elevation, partly in section, of one of said severing means and a straight-edge; Figs. 9 and 10 are a plan and front elevation of one of the knives of the severing means; Fig. 11 is a plan and front elevation of a dog forming part of the controlling mechanism for the severing means; Fig. 12 is a rear elevation, Fig. 13 a plan and Fig. 14 an end elevation (as seen from 70 the left in Fig. 12) of the sheet feeding means; Fig. 15 is a sectional view showing the means in Fig. 12 whereby the feeding means therein shown adjusts itself automatically to the sheet received thereby; Fig. 85 15 is a plan view, partly in section, illustrating a part of the means whereby the advance of the feeding means is controlled; Fig. 17 is a view of what is seen in Fig. 16, one half thereof appearing in elevation and 90 the other half in section; Fig. 17' is a front elevation of the block 29 shown in Figs. 16 and 17; Fig. 18 is a detail view illustrating a part of the means whereby the severing means is reversed, so that one of said means 95 will be brought into operative condition and the other rendered inoperative; Fig. 19 is a side elevation of a modified form of the machine; Fig. 20 is a front elevation of 10 said modified form of the machine; Fig. 21 is a plan view of the table seen in Figs. 19 and 20 and of a part of the sheet feeding means; Fig. 22 is a detail view showing in plan a fragment of that portion of the mechanism which comprises two pawls forming 10 a part of the feeding means of the machine shown in Fig. 19 and 20, together with a part of the means for controlling said pawls; Fig. 23 is a front elevation of what is seen in Fig. 22; Fig. 24 is a transverse sec- 11

tional view showing the sheet support, and parts of the sheet feeding mechanism of Figs. 19 and 20; and, Fig. 25 is a plan view of a fragment of a sheet, the same having diagrammatically illustrated thereon the manner in which the rows are formed and the scrap cut away as fast as produced.

In the base *a* is arranged a frame *b* which is pivotally supported in the base so that it may be tilted backward at any desired angle. In this frame is journaled the main shaft *c*, carrying, free thereon, a driving pulley *d* and a clutch *e* of the type shown in Fig. 31 of the U. S. Letters Patent No. 913182; it is unnecessary to describe this clutch in detail herein, in view of its full illustration and description in the said patent, it being sufficient to explain that when the handle *f* in Fig. 2 is held depressed, as by being engaged in the notched stop *g*, mechanism comes into play to lock the pulley *d* to the shaft *c*, so that said shaft will rotate with the pulley, and when said handle is released from said stop and rises under the action of the spring *h* said mechanism is caused to release the pulley from the shaft, so that the pulley runs free on the shaft.

At the back of the bed *i* of the frame *b* is arranged the lower member *j* (Figs. 2, 3 and 5) of the die mechanism, the stops afforded by the upper member *k* of which is carried by the plunger *l* guided in suitable ways in the frame *b* and actuated from a crank *m* on the shaft *c* by the pitman *n*. On the bed *i* is arranged the sheet support or table *o*, the same being adjustable forward and back thereon, that is, toward and from the die mechanism; the adjustment may be accomplished by a hand-screw *p* tapped into a depending lug *q* on the table and bearing against the front of the bed *i*, the table being kept true in adjusting it by the two pinions *r* fixed on the ends of a shaft *s* journaled in the table and meshing with fixed racks *t* on the table. At each side of the die mechanism there is bolted to the bed a bracket *u*. These brackets are reverse counter-parts of each other, so it is necessary to describe but one of them.

Referring to Figs. 6, 7 and 8 the bracket *u* is formed with a forwardly opening mouth or space *v* which is adapted to receive the rear edge of the sheet to be operated upon, and it has a laterally projecting overhang *w*. *x* denotes straight-edges disposed one on one side and the other on the other side of the brackets *u*, each being formed of a strip of angle iron and supported at its outer end by an arm *y* projecting from the table *o* and having its inner end formed with a slot *z* to receive a screw 2 in the overhang of the adjoining bracket *u*, the slots *z*, when the screws are released, allowing the straight-edges to be adjusted with the table. *3* is an inclined lip on each straight-edge

to insure the sheet-edge coming squarely to rest against the straight-edges.

When a sheet is introduced into the machine, standing in contact with one of the straight-edges, it is received by a carrier which is made to grip it and hold it firmly as it is fed lengthwise of the table *o* under the reciprocating die-member. This carrier is shown best in Figs. 5, 12, 13, 14 and 15 and it is constructed as follows: 4 is a rack having square-cut teeth 5 along its front edge and a square recess 6 near each end thereof in its rear edge, and also having an upstanding projection 7 near each end. The spacing at 5' between the two teeth at each end of the rack is greater than the spacings between the remaining teeth of the rack, all of which spacings, it may be noted, are uniform. Each recess 6 receives a square stud 8 projecting downwardly from a forked bracket 9 and affording journals for the rollers 10 and 11. The brackets 9 are formed with tables 12 and above the table each is forked in plan (Fig. 13) so as to receive the pivoted presser 13, the table and presser having a mating projection and recess 14. Each presser or jaw is normally held in the dotted line position in Fig. 14 by a spring 15 and is forced into gripping relation to the table 12 so as to indent and grip the interposed sheet by a cam 16 formed on a sectional shaft 17 carrying the handle 18 (Figs. 1, 2, 3 and 5) whereby the shaft is turned and the carrier bodily moved, in the manner to be described, along a path parallel with the straight-edges *x*. The shaft 17 is held against endwise movement by collars 19 and 20 which abut against the opposite sides of the left-hand bracket 9 in Fig. 12. The right-hand bracket 9 is capable of slight movement toward the other bracket because the recess 6 receiving its stud 8 is slightly wider than said stud, such movement being however normally resisted by a spring 21 interposed between the right-hand bracket 110 and a collar 22 fixed on the shaft. 23 is a collar fixed on shaft 17 at the right of right-hand collar 9 and housing a spring-pin 24 bearing upon a camway 25 in the side of said bracket, the wiping of the pin over said camway as the shaft is turned to cause the pressers 13 to grip the sheet producing a shifting of the right-hand bracket toward the left-hand bracket to center the sheet. The carrier is arranged to travel in the rabbit 26 at the back of the table *o*, being held therein by a plate 27 having an inside longitudinal rib 28 in the grooves beside which the rollers 11 run (Figs. 5 and 14).

As the operator, by means of the handle 18, moves the carrier, gripping the sheet, across the machine, the die mechanism operates intermittently on the sheet, forming a series or row of cuts. These cuts should be uniformly spaced from each other, and to 120

this end the manual advance of the carrier is controlled from the die mechanism as follows: Referring to Figs. 3, 16 and 17, 29 is a block set in a recess 30 in table *o* and 5 opening upon the rabbet 26, the same having a groove 31 on its under side to receive a sliding pawl 32 which co-operates with the teeth 5 of rack 4, the pawl being laterally cushioned and adapted to be adjusted laterally by turning screws 33 between which and pins 34, guided in the block and engaging opposite sides of the pawl, are interposed springs 35. The pawl is slotted to receive one arm of a bell-crank lever 36 (which arm 10 has a cushioned engagement with the pawl by virtue of a spring-pin 37 against which the arm directly bears); the bell-crank lever 36 is fulcrumed between collars 38 on the shaft *s* and its free arm is connected by a pitman 39 with a lever 40 fulcrumed in the frame *b*, the said lever being connected by a pitman 41 with a lever 42, also pivoted in the frame *b* and carrying a roller 43 bearing upon some going part, such as a cam 44 on 15 shaft *c*, the free end of lever 42 being pref-erably shaped as a handle 45. A spring 46 holds lever 40 in such position that the roller on the lever 42 normally presses against the cam. In view of this construction the pawl 32 normally restrains the rack (and hence the carrier) against advance; but on each rotation of the shaft *c* the pawl is withdrawn, releasing the rack, quickly re-turning, however, into engagement with it. 20 Thus, manual pressure being applied to the carrier to effect its advance across the machine, such advance is intermittent in character, the several increments being uniform; that is to say, all the increments are uniform 25 except the last in each direction, which, owing to the relatively augmented spacing at 5' between the last two teeth of the rack at each end thereof, is longer than the rest for a purpose to be explained hereafter in ref-30 erence to Fig. 25.

The cutting away of the scrap upon the forming of a series or row of cuts at the back of the sheet is effected as follows: Referring to Figs. 6 to 10, in each bracket 35 *u* is pivoted a knife 47 whose knife-proper 48 has shearing coaction with a fixed knife 49 secured to the front of the bracket. Overlying the front face of the knife 47 and secured to the bracket is a plate 50, the ad-40 joining outer edges of said plate and knife 49 being beveled to form a flaring entrance 51 facilitating the admission of the sheet to the mouth *v* of bracket *u*. A spindle 52 is pivoted to and projects upwardly from 45 the knife and around it is coiled a spring 53 interposed between the top of the bracket *u* and adjusting nuts 54 on the spindle and acting to hold the knife normally elevated. Before proceeding to describe how each 50 knife 47 is caused to move to shear off the

scrap it may be well to remark that the bottom surface of the mouth *v* of each bracket *u* slopes relatively outwardly (i. e., away from the other bracket) as at 55, permitting the scrap to fall down between the back of the table *o* and the adjoining straight-edge *x*. When the carrier is travel-ing in either direction the relatively remote sheet severing means is acting and the other is idle. The action of each severing means 70 is intermittent, being effected from the plunger 7, so that each time the die mecha-nism operates to form a cut the severing means operates to sheer or cut away the scrap. A sliding dog 56 (Figs. 6, 7, 8 and 80 11) is movable in a groove 57 in the front of each knife 47 so as to project from the end of the knife or recede into the same. When the dog projects from the knife it stands within the path of movement of a 85 foot 58 on the side of the plunger 7, said foot therefore depressing the knife when the plunger descends. At each end of the table *o* is fulcrumed a lever 59, the said 90 levers being connected so as to move to-gether by a link 60 and said levers being also respectively connected with the dogs 56 by links 61. Pivoted to each lever is a pawl 62 having a T-shaped head which may catch in a notch 63 in the end of the plate 27 and 95 which also lies within the path of movement of the adjoining projection 7 on the rack 4 of the carrier. Opposite the adjoining end of the rack 4 the lever 59 carries a set screw 64 against which the rack, after its 100 projection 7 has tripped the pawl 62 out of the notch 63, impinges to shift said lever and the other lever 59 on their fulcras, thereby causing one of the dogs 56 to retract and the other to project from the knives 57. 105

The operation of the machine shown in the first eighteen figures of the drawings is as follows: A sheet being placed upon the table *o* so as to enter the gripping means of the carrier it falls with its rear edge in 110 contact with the corresponding straight-edge *x*, it being understood that at this time the carrier is at one of its limits of move-ment. The operator now grasps the handle 18 and presses it downwardly, thus grip-115 ping the sheet. Having started the shaft *c* rotating by pulling down upon the handle *f*, the carrier, by means of handle 18, is manually moved across the machine, the trip mechanism so timing its intermittent 120 advances that each time the die mechanism operates to form a cut the carrier moves one step, that is, just sufficiently to bring the sheet in position for the forming of the next cut. Assuming that the carrier 125 is being advanced to the right in Fig. 2, the dog of right-hand knife 47 will be project-ing into the path of the foot 58 on the plunger, so that each time the latter de-sends a cut is formed by the right-hand 130

shearing means, a complete sequence of such cuts resulting in the part of the sheet back of the shearing line (scrap) being finally cut away. Referring to Fig. 25, A designates the first row of cuts formed by the die (1, 2, 3, and 4, etc., indicating the sequence in which the cuts occur), and A' the first line of cuts formed by the right-hand shearing means. As the rows of cuts formed by the die mechanism are staggered, by preference, to reduce the waste, the sheet remains uncut (as at X, Fig. 25) by the die mechanism at the end of each row. To prevent the die from operating on the sheet at X the last impulse which the carrier is allowed to receive in each direction exceeds all the other impulses, owing to the spacing 5' in Fig. 13, the sheet thus clearing the die mechanism before it can again be operated upon by the same. When the scrap has been entirely cleared away (the carrier now having reached its limit of movement in one direction), the operator raises the handle 18 to open the gripping mechanism of the carrier, allowing the sheet to fall again with its back edge in contact with the straight-edge. The handle 18 is now again depressed to grip the sheet, and then employed to move the carrier in the reverse direction. At the end of its first movement, the rack of the carrier tripped the right-hand pawl 62 and shifted the levers 59 so that the dog of the right-hand knife 47 was retracted and the dog of the left-hand knife projected into the path of the corresponding foot on the plunger. In the return movement of the carrier, therefore, the left hand shearing means is active and the right-hand shearing means inactive.

The operation so far as the die mechanism and shearing means is concerned is the same in the return movement of the carrier as it was in the movement thereof to the right, resulting in the row B of cuts 1, 2, 3, 4, etc., produced by the die mechanism and the line of cuts B' produced by the shearing means. Z in Fig. 25 denotes indentations formed by the projections and recesses 14 of the gripping means on the carrier. 65 denotes safety stops against either of which a toe 66 on the adjoining collar 19 or 23 of the carrier will engage to prevent the operator from turning the handle 18 to open the gripping mechanism, anticipating that the sheet is ready to be released so as to fall back against the straight-edge before the carrier has completed its full movement in either direction.

In Figs. 19 to 24, the shaft c' (carrying the loose pulley d' and a clutch e' like clutch e) has a crank 67 wherefrom, through a pitman 68, a toothed segment 69, rocking in frame b', is actuated. This segment meshes with the teeth 70 on the under side of a

rack 71 sliding in a guideway 72 in table c', the teeth 73 of said rack being engaged by either of two reversely set spring-pressed pawls 74 pivoted in a bar 75 which slides in the rabbet 26', being therein held by the plate 76. This bar (forming part of the carrier in this machine) carries two brackets 77 having inwardly extending tables 78 and forked and otherwise shaped like the brackets 9 and receiving the pivoted spring-actuated pressers 79 which are moved by the cam-shaft 80 journaled in said brackets and provided with the grooved cams 81. Housed in the top of the bar is a slide-rod 82 having two rounded notches 83 spaced farther apart than the two pins 84 on the pawls which ride on the thus-notched face of the slide-bar; when one pawl moves rearwardly and is thus engageable with the teeth 73 of the rack 71, its pin being then in one of the notches of the slide-rod, the other pawl remains withheld out of the path of the teeth. Adjustable stop-screws 85 are arranged on the table so that the end of the slide-rod will engage one of them in each direction of movement of the carrier. The severing means 86 are the same as those already described, and their dogs 87 are connected with the levers 88 (interconnected by the link 89) by the links 90. The rocking of the segment 69 is thus transmitted by one of the pawls 74 to the carrier and as the carrier reaches its limit of movement in either direction the slide-bar carried thereby contacts with a stop-screw 85 and is shifted so as to disengage that pawl from the rack and allow the other to become operative; in this way the carrier's movement is automatically reversed. It is of course necessary, when the carrier reaches its limit of movement in either direction, to cause it to release the sheet so that (the scrap having been removed) it will fall back against the straight-edge x', and this is accomplished by fixed pins 91 one of which will be received by the adjoining grooved cam 81 and cause an oscillation of the cam-shaft 80. When the sheet being operated upon is exhausted the machine stops automatically. The hand-lever f' is caused at this time to be disengaged from the stop g' (so that the clutch e' releases the pulley d') by a lever 92 connected with a slide 93, moving in a bracket 94, by the pitman 94'. The slide is held against a cam 95 rotating in said bracket by a spring 96 controlling lever 92, the said cam being given a rotary impulse each time the carrier reaches each limit of its movement by one of two pawls 97 pivoted in the right hand lever 92 and engaging a ratchet-wheel 98 fixed to the cam. To insure the sheet being operated upon falling into proper contact with the straight-edge when released by the gripping mechanism the carrier arms 99, having notched pivoted feet 100 to engage the outer edge of

the sheet, are pivoted in an upright frame 96' rising from the brackets 9'. These may be operated either by spring or positive means.

5. The broken lines C and C' in Fig. 21 illustrate the lines of operation of the die and severing mechanisms corresponding to A and A' or B and B' in Fig. 25.

Having thus fully described my invention, what I claim as new and desire to secure by Letters Patent is:—

1. In combination, with the frame, means for feeding the sheet edgewise in a predetermined path, separate alternately operating 15 means for severing the sheet in lines substantially parallel with said path, and means for operating on the sheet at substantially one side of each line, substantially as described.

20. 2. In combination, with the frame, and a sheet-engaging stop, means for feeding the sheet edgewise in a predetermined path, separate alternately operating means for severing the sheet in lines substantially parallel 25 with said path, and means for operating on the sheet substantially between each severing line and the stop, substantially as described.

3. In combination, with the frame, a 30 sheet-carrier movable in substantial parallelism with the sheet-supporting plane thereof, a sheet-engaging stop disposed at one side of the path of feeding the sheet, separate alternately operating means for 35 severing the sheet in lines substantially parallel with said path, and means for operating on the sheet substantially between each severing line and the stop, substantially as described.

40. 4. In combination, with the frame, a sheet stop, the sheet being movable substantially planiform fashion into engagement with the stop, separate alternately operating means for severing the sheet in lines crossing the 45 path of movement of the sheet toward the stop, and means for operating on the sheet substantially between each severing line and the stop, substantially as described.

5. In combination, with the frame, a sheet- 50 holding carrier movable in the frame, and separate alternately operating means for severing the sheet at one side of the path of movement of the carrier, substantially as described.

55. 6. In combination, with the frame, a sheet-holding carrier movable in the frame, means for operating on the sheet in a line substantially parallel with the path of movement of the carrier, and separate alternately 60 operating means for cutting away the part of the sheet operated upon by the first-named means, substantially as described.

7. In combination, with the frame, a sheet-holding carrier movable in the frame, 65 means for operating on the sheet in a line

substantially parallel with the path of movement of the carrier, the sheet being movable in the carrier in substantially its own plane toward the operating means, a stop to limit said movement of the sheet, 70 and separate alternately operating means for cutting away the part of the sheet operated upon by the first-named means, substantially as described.

8. In combination, with the frame, a manually moved sheet holding carrier movable in the frame, and means for alternately checking and releasing the carrier while being subjected to manual moving pressure, 75 substantially as described.

9. In combination, with the frame, a going part, a movable sheet feeding means, and a step-by-step checking means for the feeding means including coactive checking members, and means, controlled from the going part, for moving one of said members 80 intermittently into and out of engagement with the other, substantially as described.

10. In combination, with the frame, a going part, a movable sheet feeding means, and a step-by-step checking means for the feeding means including coactive checking members, and means, operated from the going part, for moving one of said members 85 intermittently into and out of engagement with the other, substantially as described.

11. In combination, with the frame, a going part, a movable sheet feeding means, and a step-by-step checking means for the feeding means including coactive rack and pawl members, and means, controlled from the going part, for moving one of said members intermittently into and out of engagement with the other, substantially as described. 100

12. In combination, with the frame, a going part, a movable sheet feeding means, and a step-by-step checking means for the feeding means including coactive rack and pawl members, and means, operated from the going part, for moving one of said members intermittently into and out of engagement with the other, substantially as described. 105

13. In combination, with the frame, a sheet-feeding means movable in the frame, alternately operating sheet-severing means, and means, controlled from the feeding means, for controlling the severing means, 110 substantially as described.

14. In combination, with the frame, a sheet-feeding means movable back and forth in the frame, alternately acting means for operating on the sheet, and means, actuated from the feeding means, for controlling the second-named means, substantially as described. 125

15. In combination, with the frame, a sheet-feeding means movable back and forth 130

in the frame, alternately acting means for operating on the sheet, and means, having parts thereof disposed in the path of movement of the feeding means, for controlling 5 the second-named means, substantially as described.

16. In combination, with the frame, a sheet feeding member movable therein, a going part, sheet shearing means, a dog 10 interposable between the going part and the movable member of the shearing means, and mechanism, controlled from the feeding member, for controlling the dog, substantially as described.

15 17. In combination, with the frame, a sheet feeding member movable back and forth therein, a going part, separate sheet shearing means, and means, controlled from the going part, for rendering one shearing 20 means active and the other inactive, on one stroke, and vice versa on the next succeeding stroke, of the feeding means, substantially as described.

18. In combination, with the frame, a sheet-feeding member comprising a sheet-gripping means, the sheet being movable in substantially its own plane in said member, said member being movable crosswise of the path of movement of the sheet therein, a 25 sheet-stop disposed at one side of the path of movement of said member, and means for severing the portion of the sheet adjoining the stop, substantially as described.

19. In combination, with the frame, a sheet feeding member comprising a sheet-gripping means, the sheet being movable in substantially its own plane in said member, and said member being movable rectilinearly crosswise of the path of movement of the sheet therein, a straight-edge arranged parallel 30 with the path of movement of said member, and means for severing the portion of the sheet adjoining the straight-edge, substantially as described.

45 20. In combination, with the frame, an elongated rectilinear sheet-stop, means for feeding the sheet in a path parallel with said stop, and separate alternately operating means for severing the portion of the sheet 50 adjoining the stop, substantially as described.

21. In combination, with the frame, an elongated rectilinear sheet-stop, means for feeding the sheet in a path parallel with said stop, separate alternately operating 55 means for severing the portion of the sheet adjoining the stop, and means for securing the sheet in the feeding means during the severing operation, substantially as described.

60 22. In combination, with the frame, an elongated rectilinear sheet-stop, means for feeding the sheet in a path parallel with said stop, means for operating upon the portion of the sheet adjoining the stop, and alternately operating means for severing the 65

portion of the sheet operated upon, substantially as described.

23. In combination, with the frame, means for operating upon the sheet, a sheet-feeding member movable in the frame, a sheet gripping mechanism carried by said member and comprising a movable part, and means, disposed in the path of movement of said movable part with said member, for actuating said part, substantially as described. 70 75

24. In combination, with the frame, means for operating upon the sheet, a sheet feeding member movable in the frame, a sheet gripping mechanism carried by said member and comprising a movable part having a cam, and means, disposed in the path of movement of said movable part with said member, to engage the cam and thereby actuate said part, substantially as described. 80 85

25. In combination, with the frame, means for feeding the sheet in the frame, a rectilinear stop disposed parallel with the path of feeding the sheet, means for securing the sheet in the feeding means, means for forcing the sheet toward the stop, 90 means for severing the portion of the sheet adjoining the stop, and means for periodically releasing the sheet in the feeding means, substantially as described. 95

26. In combination, with the frame, means for feeding the sheet in the frame, a stop disposed parallel with the path of feeding the sheet, means for securing the sheet in the feeding means, means for severing the portion of the sheet adjoining the stop, 100 means for forcing the sheet toward the stop, and means for periodically releasing the sheet in the feeding means, substantially as described. 105

27. In combination, with the frame, means for feeding the sheet intermittently in the frame, a stop disposed parallel with the path of feeding the sheet, means for securing the sheet in the feeding means, means for forcing the sheet toward the stop, 110 means for severing the portion of the sheet adjoining the stop, and means for releasing the sheet upon each stroke of the feeding means, substantially as described. 115

28. In combination, with the frame, a work-carrier movable back and forth therein in a definite path, two severing means having their severing lines substantially parallel with said path, and means, coöperating with the carrier, for rendering one severing means active and the other inactive, and vice versa, on each stroke of the carrier, substantially as described. 120

29. In combination, with the frame, a work-carrier movable back and forth therein in a definite path, two severing means having their severing lines substantially parallel with said path and aligned with each other, means for gaging the adjust- 125 130

- ment of the work crosswise of said path and means, coöperating with the carrier, for rendering the severing means active and the other inactive, and vice versa, on each stroke 5 of the carrier, substantially as described.
30. In combination, with the frame, a carrier movable back and forth therein in a definite path, two severing means having their severing lines substantially parallel 10 with said path, means for gaging the adjustment of the work crosswise of said path, means operating to move the work crosswise of said path, and means, coöperative with the carrier, for rendering one severing 15 means active and the other inactive, and vice versa, on each stroke of the carrier, substantially as described.
31. In combination, with the frame, means for feeding the sheet edgewise first 20 in one direction and then in the other, means for operating on the sheet during its movement in each direction, and means for cutting the sheet longitudinally of its path of feeding movement during the feeding of 25 the sheet in each direction, substantially as described.
32. In combination, with the frame, means for feeding the sheet edgewise first 30 in one direction and then in the other, means for operating on the sheet during its movement in each direction, and means for cutting the sheet at one side of the second-named means during the movement of the sheet in one direction and for cutting the 35 sheet at the other side of the second-named means during the movement of the sheet in the other direction, substantially as described.
33. The combination with a punching 40 press of a movable feed table having solely a lateral movement, guiding means therefor restraining it to a determined path, manually controlled clamping means on said table for gripping a sheet to be punched, whereby the sheet is carried with the table in its lateral movement, but may be fed forward independently of the table, and feed-controlling stops for limiting the feeding movements of said table.
- 45 34. The combination with a punching press of a movable feed table having solely a lateral movement, guiding means therefor restraining it to a determined lateral path, said table having stop teeth, a movable stop at a fixed location, engaging said teeth, and means operated by the press for reciprocating said stop to withdraw it and permit a feeding movement of the table after each punching operation.
- 50 35. The combination with a punching 55 press of a movable feed table having solely a lateral movement, guiding means therefor restraining it to a determined lateral path, said table having an operating handle and clamps on said feed table for gripping the sheet operatively engaged by said handle.
36. The combination with a punching press of a movable feed table having solely a lateral movement, guiding means therefor restraining it to a determined path, clamp- 70 ing levers on said table for gripping the sheet, and an operating handle carried by the feed table and overlying said levers, and adapted upon being turned to operate said levers.
37. The combination with a punching press of a movable feed table having solely a lateral movement, guiding means therefor restraining it to a determined path, clamp- 75 ing levers thereon at opposite sides for gripping the opposite margins of the sheet, and an operating handle extending laterally over the feed table, having eccentric portions engaging said levers, whereby upon turning the handle the levers are simultaneously operated.
38. The combination with a punching press having a punch and scrap cutter, of a movable feed table having solely a lateral movement, clamping means on said table 80 for gripping a sheet to be punched, and a stationary gage related to said scrap cutter for limiting the forward feed of the sheet relatively to the table to the correct 85 distance between lateral rows of punchings.
39. The combination with a punching press of a feed table having solely a lateral movement, said table adapted to carry a sheet to be punched and to permit said sheet to be fed forward over the table, and clamping means on said table for gripping such sheet, whereby the lateral feed of the sheet is performed by moving said table, and the forward feed of the sheet between rows is performed by releasing said clamping 95 means and moving the sheet relatively to the table.
40. The combination with a punching press of a feed table having solely a lateral movement, said table adapted to carry a sheet to be punched and to permit said sheet to be fed forward over the table, and clamping means on said table for gripping such sheet, and means for locating the stopping points of said table in its lateral feed- 100 105 ing movements.
- In testimony whereof I affix my signature in presence of two witnesses.
- AMOS CALLESON.
- Witnesses:
- W. C. HORN,
LOUIS F. STUMPF.
